UNITED STATES PATENT OFFICE

FREDERICK ROSENBERG, OF KEW GARDENS, NEW YORK, ASSIGNOR TO WILLIAM
WILLHEIM CO., INC., OF NEW YORK, N. Y.

DESIGN FOR A TEXTILE FABRIC OR SIMILAR ARTICLE

Application filed October 14, 1932. Serial No. 45,336. Term of patent 3½ years.

To all whom it may concern:

Be it known that I, FREDERICK ROSENBERG, a citizen of the United States of America, residing at 118-80 Metropolitan Avenue, Kew Gardens, Long Island, New York, have invented a new, original, and ornamental Design for a Textile Fabric or Similar Article, of which the following is a specification, reference being had to the accompanying drawing, forming a part thereof.

The figure is a plan view of a textile fabric showing the complete width of my new de-

sign, except for the portion between the break lines which is similar to that on either side thereof. The dot and dash lines on the drawing outline the design unit, which unit is repeated in regular succession as indicated by the extensions beyond the unit boundaries.

I claim:

The ornamental design for a textile fabric or similar article as shown and described.

In testimony whereof I have signed this specification.

FREDERICK ROSENBERG.
